UNITED STATES PATENT OFFICE.

JOHN BACHMANN, OF CHICAGO, ILLINOIS.

TOBACCO-PIPE.

1,021,442.

Specification of Letters Patent. Patented Mar. 26, 1912.

Application filed September 26, 1910. Serial No. 583,973.

To all whom it may concern:

Be it known that I, JOHN BACHMANN, a citizen of the United States, residing at Chicago, in the county of Cook and State of Illinois, have invented certain new and useful Improvements in Tobacco-Pipes, of which the following is a description.

My invention belongs to that general class of devices known as tobacco pipes, and relates particularly to a straight or bent stem pipe, having an even or continuous unobstructed passage through the pipe from the mouth piece to the exterior of the bowl, and provided with a closure for normally closing the end of the passage at the exterior of the bowl when the pipe is in use.

My invention has among its objects the production of a simple, convenient, efficient and satisfactory pipe of the kind described that may be easily and perfectly cleaned.

To this end my invention consists in the novel construction, arrangement and combination of parts herein shown and described, and more particularly pointed out in the claims.

In the drawings, wherein like reference characters indicate like or corresponding parts, Figure 1 is a side elevation of a straight stem pipe with a cleaner therein. Fig. 2 is a longitudinal sectional view of the same, the cleaner removed. Fig. 3 is a similar longitudinal sectional view of the curved stem pipe. Fig. 4 is a plan view of the preferred form of closure. Fig. 5 is a sectional view of the same, and Fig. 6 is a perspective view of the closure removed from the pipe.

Referring to the drawings, 1 represents the bowl of the pipe provided with a stem 2 and mouth piece 3, which stem and mouth piece may be formed integral or separate, as shown in the drawings. The bowl 1 is provided with the usual tobacco chamber of any desired shape. Extending through the pipe stem and bowl from end to end is an even or continued passage *a*, which is preferably so arranged that it includes the lower portion of the chamber in the bowl. The passage from the stem to the chamber is always open when the pipe is in use, the end of the passage at the exterior of the bowl being preferably normally closed by a plug or closure *b* of any suitable material, which may be retained in position in any desired way. As shown, the plug *b* is preferably rotatable and arranged with its axis of ro-

tation inclined, or at an angle to the passage *a*. The closure or plug *b* is provided with an opening *a*¹ therethrough, which is also inclined or at an angle to the axis of rotation of the plug, so that when the plug is in position substantially as shown in Figs. 2 to 5 inclusive, the passage *a* and *a*¹ is continuous and open throughout the length of the pipe, so that a suitable cleaner may be inserted and pulled back and forth, thoroughly cleaning the pipe throughout the length of the passage, and at the same time cleaning the bottom *C* of the bowl.

When the closure is turned part way around, the duct or passageway *a*¹ in the closure is substantially as indicated by the dotted lines in Fig. 5, closing the passageway *a* as shown. The plug *b* is provided with a slot in the same so that it may be turned with the finger nail, a knife blade, a coin, or the equivalent. The plug *b* may be maintained in position in any desired way, as shown it is preferably locked on the pipe by a cup-shaped part *e* of suitable material, preferably metal, which is outwardly flanged at the exterior of the pipe and then inwardly flanged over the end of the plug *b*, thereby maintaining or locking the same in the cup so that it is never necessary to remove the plug from the pipe to clean the same. The inwardly flanged portion of the cup *e* engages the plug with sufficient friction to prevent any accidental turning thereof but to readily permit the same to be turned whenever desired by the insertion of a tool or the finger nail in the slot formed in the plug for this purpose. The cup-shaped parts *e* are retained in position on the pipe in any desired way, small nails or brads being shown for the purpose. It will be noted that with this construction the plug or closure cannot become lost or injured, being always protected and retained in position; that there are no threads to wear, nor can the plug drop out while the pipe is being used.

Where the pipe stem is made up of two parts 2 and 3, as shown in the drawings, I provide the usual connecting piece or coupling *D*, which, however, is fitted tightly to both pieces so that there is no open space for the juice or nicotin to settle in. By being closely fitted, the passages in the stem and mouth piece are always in alinement, so that there is no shoulder or obstruction to interfere with the pipe cleaner. Inasmuch

as the passage is continuous throughout the pipe stem, it is never necessary to remove the stem 3, or mouth piece, as is the case with the ordinary pipe when cleaning the 5 same. With the ordinary pipe, when the pipe cleaner is pushed in the stem toward the bowl and drawn back, if the mouth piece 3 has not been removed the nicotin or tobacco juice is drawn into the mouth piece. 10 The only way to avoid this is to remove the stem and pass the cleaner through from the mouth end. However, in continually cleaning the pipe, the threads in one of the parts will sooner or later become worn so that 15 the removable stem does not fit tightly and nicotin will gather at one or the other, or both ends of the plug D.

With my pipe cleaner there is no necessity for removing the mouth piece 3, as the 20 cleaner can be worked back and forth and finally drawn through the passage a^1 out through the plug b.

It will be particularly noted that with 25 my pipe the passage a need not be increased in size over the passages in the pipes in use, and the only metal that the smoke or nicotin can come in contact with when the closure b is closed is an area equal to the area of the passageway, which is comparatively 30 small. The plug b can be fitted to old pipes in use, or to new pipes during the manufacture, but in the first instance, however, if there is not a tight fit at the plug or coupling D, it should be corrected.

Having thus described my invention, it is obvious that various immaterial modifications may be made in the same within the scope of the appended claims, hence I do not wish to be understood as limiting myself to the exact construction, arrangement 40 or combination of parts herein shown and described.

What I claim as new and desire to secure by Letters Patent is:—

45 1. A tobacco pipe comprising a chambered bowl, and a stem provided with a continuous unbroken passage therethrough to the exterior of the bowl, and including a portion of the chamber in said bowl, and means normally closing the end of the passage at the exterior of the bowl comprising a closure rotatably mounted in said bowl and adapted to normally overlie and close the end of said passage, said closure being provided with an eccentrically disposed port

extending therethrough adapted upon rotation of said closure to be brought into registration with said passage to form a continuation thereof.

2. A tobacco pipe comprising a chambered 60 bowl and a stem provided with a continuous passage therethrough to the exterior of the bowl, and including a portion of the chamber in said bowl, said passage being of substantially uniform diameter throughout 65 its length, and a movable element for the end of said passage permanently secured to said bowl and normally closing the end of the passage, said closure being provided with a port extending therethrough of substantially 70 the same diameter as said passage and adapted to align therewith in one position of the closure to form a continuation thereof whereby there is provided a continuous passage of substantially uniform 75 diameter for a cleaner through the stem, bowl and closure.

3. A tobacco pipe comprising a chambered 80 bowl and a stem provided with a continuous passage therethrough to the exterior of the bowl, and including a portion of the chamber in said bowl, said passage being of substantially uniform diameter throughout 85 its length, said bowl being provided with a circular recess in the exterior thereof, 90 a closure rotatably mounted in said recess and fitting snugly against the bottom thereof, said closure being provided with a port extending therethrough adapted to register with the passage in the pipe, and means for 95 permanently securing said closure in position and arranged to frictionally hold the same against rotation.

4. A tobacco pipe comprising a chambered 95 bowl and stem provided with a continuous passage therethrough to the exterior of the bowl, and including a portion of the chamber in said bowl, said bowl being provided with a circular recess in the exterior thereof, a closure rotatably mounted in said recess and provided with a port extending therethrough adapted to register with the passage in the pipe, and a circular metallic 100 flange secured to the exterior of said bowl and overlying the outer surface of said closure. 105

JOHN BACHMANN.
